(57) **CLAIM**

The ornamental design for a SXS switch, as shown and described.

DESCRIPTION

FIG. 1 is a front-left perspective of the switch.

FIG. 2 is a front view of the switch.

FIG. 3 is a back view of the switch.

FIG. 4 is a top view of the switch.

FIG. 5 is a bottom view of the switch.

FIG. 6 is a left side view of the switch; and,

FIG. 7 is a right side view of the switch.

The broken lines in the drawings depict portions of the SXS switch that form no part of the claimed design.
